BOAT STERN VACUUM RELIEVING ATTACHMENT

Luther T. Dunning, Norfolk, Va.

Application May 25, 1954, Serial No. 432,106

5 Claims. (Cl. 114—67)

This invention relates to devices for increasing efficiency of boats, and in particular means for relieving the vacuum or cavitation to the rear of the stern board of a boat and between the bottom of the boat and the surface of the water.

The purpose of this invention is to provide means for supplying a current of air to an area to the rear of the stern board of a boat to relieve the pulling force resulting from the vacuum formed by water rushing over the sides of the boat.

The rush of fluid over the sides of an object passing through the fluid evacuates the fluid and air from an area directly behind the object causing a vacuum or partial vacuum generally referred to as cavitation and this area provides a direct pulling force in the direction opposite to that in which the object is traveling and as the power required to move the object forwardly must be sufficient to overcome this force the efficiency of an engine or other driving power unit of a boat, airplane or motor vehicle is reduced.

Various attempts have been made to supply currents of air to this area, however, all attempts to supply air to an area to the rear of a stern board of a boat have not been successful because the air is not supplied at the proper point.

With this thought in mind, this invention contemplates an auxiliary stern board spaced from and positioned to the rear of the conventional stern board of a boat whereby an area is provided to the rear of the conventional stern board for the circulation of air and the presence of a vacuum at the stern of a boat with the auxiliary stern board thereon draws air downwardly through the passages whereby the vacuum is relieved.

The object of this invention is, therefore, to provide means for forming the stern of a boat whereby the suction of a vacuum area following the stern board draws air through the stern board into the vacuum area.

Another object of the invention is to provide means for relieving the vacuum area following the stern board of a boat in which the relieving means is adapted to be attached to boats now in use.

A further object of the invention is to provide an attachment for the stern of a boat whereby vacuum following the stern is relieved in which the attachment is of a simple and economical construction.

With these and other objects and advantages in view, the invention embodies a panel of substantially the same pattern as the stern board of a boat with vertically disposed spacing cleats positioned on the forward side of the panel and means for attaching the panel with the cleats thereon to the stern board of a boat.

Other features and advantages of the invention will appear from the following description taken in connection with the drawing, wherein:

Figure 1 is a side elevational view showing the hull of a boat with the auxiliary stern board mounted at the stern and with air currents indicated by broken lines and arrows flowing between the auxiliary stern board and

2

conventional stern board whereby vacuum or cavitation at the stern of the boat is relieved.

Figure 2 is a cross section taken on line 2—2 of Figure 1 with the parts shown on an enlarged scale showing the cleats for mounting the auxiliary stern board positioned on the stern board of the boat.

Figure 3 is a plan view of the stern of the boat with the forward portions thereof broken away showing the air circulating areas between the stern board and auxiliary stern board.

Figure 4 is a detail showing a modification wherein an auxiliary stern board is provided with openings spaced downwardly from the top of the boat.

Figure 5 is a view of the auxiliary stern board, taken on line 5—5 of Figure 4.

Referring now to the drawing wherein like reference characters denote corresponding parts, the vacuum relieving attachment of this invention includes a panel 10 substantially of the same size and pattern as that of a stern board 11 of a boat 12 and cleats 13, 14 and 15 positioned between the panel 10 which provides an auxiliary stern board and the stern board 11.

As illustrated in Figure 3, the cleats are secured to the panel 10 with nails or other fasteners, as indicated by the numeral 16, and the panel 10 with the cleats thereon is secured to the stern board 11 with fasteners such as nails or screws 17.

The lower ends of the cleats 13 and 15, at the sides of the boat, are provided with beveled surfaces 18 and 19, respectively, which facilitate circulation of air through areas 20 and 21 between the panel 10 and stern board 11.

The stern board 11 is connected to sides 22 and 23 and a bottom 24 of a boat by conventional means and, as illustrated in Figure 1, with the boat positioned in water, as indicated by the numeral 25, a lower edge 26 of the panel 10 extends downwardly to the lower surface 27 of the bottom of the boat and with the boat traveling forwardly a vacuum area 28 would be produced directly following the stern board and panel. A vacuum causes suction and with the vacuum surrounded by water the suction would be directly applied to the lower ends of the passages 20 and 21 whereby air, as indicated by the arrows 29, would be drawn downwardly through the passages 20 and 21 to fill the vacuum. By this means the vacuum is continuously relieved and the pulling force resulting therefrom eliminated.

In the design shown in Figures 4 and 5 an auxiliary stern board 30, similar to the panel 10, and which is provided with cleats 31, 32 and 33, is attached to a stern board 34 of a boat 35, and in this design the upper ends of air channels 36 and 37 between the conventional and auxiliary stern boards are sealed by a strip 38. The auxiliary stern board 30 is provided with openings, as indicated by the numeral 39, whereby air is admitted to the channels 36 and 37 at points spaced below the upper end of the stern of the boat, as indicated by the arrows in Figure 4.

It will be understood that modifications, within the scope of the appended claims, may be made in the design and arrangement of the parts without departing from the spirit of the invention.

What is claimed is:

1. A boat having a hull with side walls, a bottom and a stern board, means for providing open vertically positioned air circulating channels terminating in a plane parallel with the bottom said openings being adjacent to and parallel with the stern board.

2. A boat having a stern board with open vertically disposed air circulating channels extended therethrough parallel therewith and terminating in a plane parallel with the lower end of the stern board.

3

3. In a vacuum relieving attachment, the combination which comprises a boat having a bottom, side walls and a stern board and an auxiliary stern board spaced from and parallel with the stern board of the boat and attached thereto providing open vertically disposed air circulating channels between the auxiliary stern board and the stern board of the boat said openings terminating in a plane parallel with said bottom.

4. In a vacuum relieving attachment for a boat, the combination which comprises a boat having a hull with a bottom, side walls and a stern board, an auxiliary stern board positioned parallel to and spaced from the stern board of the boat, vertically disposed cleats positioned between the auxiliary stern board and stern board of the boat providing spacing means and suitable fasteners securing the auxiliary stern board and cleats to the boat, said auxiliary stern board having openings therethrough and said openings being spaced from the upper end thereof.

5. In a vacuum relieving attachment for a boat, the 20

combination which comprises a boat having a hull with a bottom, side walls and a stern board, an auxiliary stern board positioned parallel to and spaced from the stern board of the boat, vertically disposed cleats positioned between the auxiliary stern board and stern board of the boat providing spacing means and suitable fasteners securing the auxiliary stern board and cleats to the boat, said auxiliary stern board having openings therethrough and said openings being spaced from the upper end thereof, the upper ends of openings between the conventional and auxiliary stern boards being closed.
